UNITED STATES PATENT OFFICE.

JOSEPH BROCK, OF ERIE, PENNSYLVANIA, ASSIGNOR OF FIVE PER CENT TO JOHN J. GRANT, OF ERIE, PENNSYLVANIA.

HORSESHOE-PUNCHING MACHINE.

Application filed November 12, 1919. Serial No. 337,382.

To all whom it may concern:

Be it known that I, JOSEPH BROCK, a citizen of the United States, residing at Erie, in the county of Erie and State of Pennsylvania, have invented new and useful Improvements in Horseshoe-Punching Machines, of which the following is a specification.

This invention is designed to punch horseshoes, the punching being done with group series of punches so that all the holes are punched at once.

The invention is illustrated in the accompanying drawings as follows:

Fig. 1 shows a plan view of the machine.

Fig. 2 a section of the feed-guide with the shears.

Fig. 3 a central cross section of the machine on the line 3-3 in Fig. 4.

Fig. 4 a section on the line 4-4 in Fig. 3.

Fig. 5 is an elevation of the machine from the right of Fig. 3.

Fig. 6 is an enlarged section of the punches and adjacent parts corresponding to the section in Fig. 4.

1 marks the base of the machine, 2 the frame extending upwardly from the base, and 3 the table or top of the machine.

The uprights are provided with guide ways 4 in which operate the U-shaped ends 5 of a plunger 5^a. The plunger is provided with journal pins 6 from which the connecting rods 7 extend to cranks 8, the cranks being carried by a shaft 9. The shaft 9 is journaled in bearings 10. A gear 11 is fixed on the shaft 9 and is driven by a gear 12 carried by a shaft 13. It will be readily seen that as the shaft 9 is rotated the plunger 5^a is reciprocated in the guides.

40 A feed-guide 14 is arranged on the table and a bar 15 is carried by this guide. It is carried forward by a pawl 16 which is adapted to drop into notches 17 formed in the bar as the bar is formed. The pawl 16 is carried by a rod 18, the rod being mounted on a guide 19. A connecting rod 20 extends from the rod 18 to a crank 21 on the gear 11. It will be readily seen that the pawl is reciprocated with each revolution of the gear and this forward movement of the bar is timed with the plunger so that the forward movement takes place with the plunger in an elevated position and a backward movement takes place when the plunger is moved downwardly. A dog 22

engages the side of the bar, the dog being yieldingly pressed against the bar by a spring 22^a. The dog is so formed as to prevent a return movement of the bar.

A clamping plate 23 is slidably mounted 60 in guides 25 arranged on the table 3. A shear blade 26 is carried by the plunger and operates in connection with a shear blade 27 so as to cut the bar and form the blank 15^a. The blank as it is sheared is deposited on 65 the clamp plate 23.

The clamping plate is reciprocated through the following mechanism:—Ears 28 extend downwardly from the clamping plate. A rock lever 30 extends between the 70 ears and is pivotally connected therewith by a pin 29. The lever is journaled on a rod 32 carried by a bracket 31 extending from the lower side of the table. The lower end of the lever 30 extends into a cam slot 33 in 75 a cam 33^a on the shaft 9. The cam slot 33 is so formed as to time the movement of the clamping plate to perform the functions hereinafter described. A die 35 is mounted in a plate 36 carried by the table and a 80 clamping block 37 opposes the clamping plate 23 in securing the blank 15^a in proper position on the die. The bar has the depressions 38 in which the punched holes are arranged, the depressions being for the purpose of receiving the nail heads on the shoe and the clamping mechanism positions the bar so as to bring these depressions in alignment with the openings of the die 35.

85 Punches 39 are carried in sliding blocks 90 40 mounted in slots 41 in the plunger, the plunger being provided with guide ways 42 at the sides of the slots 41 for receiving the blocks 40. The upper ends of the punches are screw-threaded and are secured in the 95 block by being screwed therein. The upper ends of the punches are slotted at 44 and locking pins 45 are arranged in these slots thereby locking the punches in adjustment. The pin 45 is secured to the block by 100 screws 46.

105 The punches extend through the guide blocks 47, these guide blocks being similar in length to the blocks 40 and having a series of openings through which the punches extend. Plates 48 are secured by means of studs 49 on the ends of the guide blocks 47 and the dies 35. These plates extend up against the ends of the punch blocks 40 and consequently align the dies, guide blocks and punch 110

blocks. The punch blocks slide within the plates 48. Similar plates 51 are arranged at the inner ends of the blocks, the plates being secured to the dies and guide blocks 5 by studs 52, the punch block 40 sliding between the plates 48 and 51. Springs 54 extend between the plates 51 and tend to draw the blocks and dies toward each other. The plates 51 are provided with the cams 55 10 which are engaged by a cam block 56 carried by the plunger. As the plunger is lifted the cam block 56 engages the cam 55 and forces the blocks carrying the punches apart against the action of the springs 54. Posts 15 58 extend upwardly from the table 3 and arms 59 are pivotally mounted on the posts by means of pins 60. Links 61 connect the arms 59 with the end plates 48. The arms have the flaring fingers 62 arranged at their 20 lower ends.

The operation of the mechanism for placing a blank under the punches and positioning it with relation to the punches is as follows:—The blank being deposited on the 25 clamping plate 23, the clamping plate is retracted. A stop 24 prevents the blank 15^A moving with the clamping plate 23 and the blank drops off the front end of the clamping plate on to the projecting fingers 34 on the front end of the clamping plate. As the clamping plate is carried forward the blank is carried forward by the clamping plate into position under the punches. Just prior to the final squeeze between the clamping 30 plate and the clamping block 37 the plunger starts its downward movement, thus moving the cam block 56 from between the cam surfaces 55 and this permits the springs to operate in drawing the punching blocks, 35 guide blocks and dies inwardly. It also swings the arms 59 inwardly until these arms engage the ends of the blank 15^A. As soon as this point in the travel of the plunger is reached the cam plate is given the final movement to fully clamp the blank. This final action of the clamping plate may 40 be omitted if desired and the punches will be moved lengthwise of the plunger slightly under the influence of the springs 54 so as to position the punches. I prefer, however, the positioning of the blank as it is the lighter of the two and all that is necessary is to so form the cam slot as to effect the result.

55 The difficulty with punching horse-shoe blanks is that due to the heat, differences in temperature and quality of the iron and rolling it is practically impossible to make the blanks of uniform length and with uniform relation between the depressions 38. Where the blank is slightly longer this elongation is fairly uniform from end to end. Consequently it is desirable not only to separate the series of punches but also to rectify their position relatively to the ends

of the blank incident to the elongation of the space between the depressions and the end of the blank. This is accomplished by the swinging arms 59 which give to the blocks slightly less movement than is involved in the variation in the length of the blank. Consequently the punches are positioned not only with relation to the total variation but also with relation to the slight variation between the end of the blank and the depression. 70

The clamping block 37 has openings 63 and studs 64 are arranged in these openings and extend from the back edge of the clamping block into the table. Springs 65 are arranged on the studs and operate against the head 66 on the studs and the end of the slot to yieldingly hold the clamping block in a rearward position. The clamping block has a cam surface 67 along its edge. A plunger 68 of U-shaped form (see Fig. 4) is slidingly mounted on the face of the uprights 2 and held in place by a strap 69. The plunger is held in its lower position by a spring 70 and the downward movement is limited by a shoulder 71 engaging the strap 69. The upper end of the plunger is provided with a cam surface 72 adapted to operate on the cam surface 67. A cam 74 is mounted on the shaft 9 and engages a cam surface 73 on the plunger 68 so as to lift the plunger. The cam throw is so timed as to lift this plunger just after the retraction of the clamping plate 23, its purpose being to give to the clamping blocks 37 a slight quick forward movement so as to force the blank off the die and leave the way clear for an incoming blank. 90

What I claim as new is:—

1. In a horse-shoe punching machine, the combination of two series of punches in alignment; means for separating the two series; mechanism for advancing a blank with the two series separated; and devices for bringing the two series together after the blank is in position under the punches. 105

2. In a horse-shoe punching machine, the combination of two series of punches in alignment; means for separating the two series; mechanism for advancing a blank with the two series separated; and devices for bringing the two series together and gauging the position of the punches by the ends of the blank. 110

3. In a horse-shoe punching machine, the combination of two series of punches in alignment; means for separating the two series; mechanism for advancing a blank with the two series separated; and devices for bringing the two series together after the blank is in position under the punches, said devices having stops contacting the ends of the blank to position the punches. 120

4. In a horse-shoe punching machine, the combination of two series of punches in 130

alinement; means for yieldingly drawing them together; means for separating them to permit the insertion of a blank; devices for feeding the blank laterally into position under the punches; apparatus for gauging the punches relatively to the blank by engagement with the ends of the blank; and means for feeding a blank longitudinally to said devices and for severing the blank in position on the devices.

16. In a horse-shoe punching machine, the combination of two series of punches; means for feeding a blank to position under the punches laterally; a clamp comprising a clamping block for engaging a blank while being punched; and means for actuating the block to discharge the blank.

17. In a horse-shoe punching machine, the combination of two series of punches in alinement; a clamping plate for moving a blank into position under the punches and for clamping the same; a clamping block opposing the clamping plate; means for moving the clamping plate; and means for actuating the block to discharge the blank.

18. In a horse-shoe punching machine, the combination of two series of punches in alinement; a clamping plate for moving a

blank into position under the punches and for clamping the same; a clamping block 30 opposing the clamping plate; means for moving the clamping plate, the clamping block having a cam surface at its rear edge; a plunger having a cam surface engaging the cam surface on the block; and means for actuating the plunger to remove the blank. 35

19. In a horse shoe punching machine, the combination of two series of punches in alinement; means for adjusting said punches relatively to each other in the line of the 40 punches; means for feeding a blank into position under the punches; and means for adjusting the blank endwise relatively to the punches.

20. In a horse shoe punching machine, the combination of two series of punches in alinement; means for adjusting said punches relatively to each other in the line of the 45 punches; means for feeding a blank into position under the punches; and means for adjusting the blank endwise relatively to the punches and as the punches are adjusted. 50

In testimony whereof I have hereunto set my hand.

JOSEPH BROCK.
